A. Hexdall, INVENTOR
BY Victor J. Evans
ATTORNEY

UNITED STATES PATENT OFFICE

ANDREW HEXDALL, OF MORRIS, ILLINOIS

SHEET-METAL-CUTTER ATTACHMENT FOR ELECTRIC MOTORS

Application filed September 1, 1928. Serial No. 303,471.

This invention relates to a tin cutting attachment for electric motors and the like, the general object of the invention being to provide a curved knife which is adapted to be forced through the tin or other sheet metal to be cut and a reciprocating member for forcing the tin against the edge of the knife, with means for reciprocating the member by a shaft provided with an eccentric and which is driven from the motor or other power means.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:—

Figure 1 is an elevation of the device.

Figure 2 is a side or bottom view thereof.

Figure 3 is a side view of the knife.

Figure 4 is an edge view thereof.

Figure 5 is an edge view of the body of the device.

Figure 6 is an end view showing the eccentric on the shaft.

Figure 7 is a perspective view of the reciprocating member and the parts associated therewith.

In these views, the numeral 1 indicates the body of the device which is of forked construction and which is formed with a centrally arranged bore 2 which rotatably supports the shaft 3, said shaft having an enlarged head 4 which carries an eccentrically arranged pin 5 on which is arranged a roller 6, it being seen that the head, with the parts thereon, are arranged between the prongs of the body.

A grooved block 7 is fastened to a shaft 8 which has its ends extending through holes in the prongs and a pin 9 is fastened to one end of the block and engages a hole in one of the prongs, said pin acting to prevent rocking movements of the block during its reciprocatory movement, which is transmitted thereto

by the eccentrically arranged roller on the head of the shaft 3 fitting in the groove of the block. A substantially triangular-shaped member 10 is fastened to the projecting end of the shaft 8 and a curved cutting blade 11 of substantially hook shape, formed with a U-shaped member 12 on its inner end, is fastened to the outer wall of one of the prongs, with the member 10 passing between the space formed by the hook-shaped part of the blade 60 so that this member 10 will act to force the metal being cut against the edge of the blade so that the metal will be cut and pushed outwardly, as shown in dotted lines in Figure 1, where A indicates the sheet being cut and A' 65 indicates the cut part of the sheet.

The shaft 3 is adapted to be fastened in the end of an electric motor, as shown at 13 in Figure 1, or it may be fastened to any other power device whereby the shaft will be rotated from said device.

From the foregoing it will be seen that by pressing the knife through a sheet of tin or other metal and then starting the power device, the rotary movement of the shaft 3 will 75 cause a reciprocating movement of the block 7 and the shaft 8 to which the member 10 is attached and thus this member will force the metal against the edge of the knife so that the metal will be cut. Both the member 10 and 80 the edge of the blade 11 should be made of case-hardened steel.

The preferable way of using the device is to place the sheet of metal to be cut on a support and to hold the device with the blade lowermost so that the block and the shaft 8 will reciprocate in a vertical plane. As will be seen, the curved edge of the member 10 acts with the cutting edge of the blade to give a shearing cut to the material being operated upon. At the beginning of the operation, an edge of the metal is placed on the blade in such a manner that said edge extends into the space formed by the hook shaped part of the blade so that said edge is under the member 95 10. Thus when said member moves downwardly, it will force the metal against the cutting edge of the blade and thus cut the metal and push the cut portion in the position shown at A' in Figure 1.

With this invention, it is possible to cut in any direction to a right angle direction to the right and in any direction to the left in the one operation without removing the device from the metal or suspending cutting operation, and that square corners can be cut with the machine without mutilating any part of the sheet metal.

I also prefer to make the cutting part of the blade 11 removable so that this part can be removed and sharpened or replaced by a new part when dulled. This removable part is shown at 11' and occupies a recessed part of the blade 11 and is fastened in place by a screw 11".

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:—

1. A device of the class described comprising a body, a reciprocating member supported thereby, means for reciprocating the member, a cutting member on the end of the reciprocating member and a curved blade attached to the body and against the cutting edge of which the cutting member forces the material to be cut during the reciprocating movement of said cutting member, said blade extending substantially at right angles to the line of movement of the reciprocating member and curving outwardly whereby a sheet of metal can be placed between the blade and the reciprocating member to cause said member to press the sheet against the blade to cut the same.

2. A device of the class described comprising a body of forked construction and having a centrally arranged bore therein, a shaft rotatably mounted in the bore, a pin eccentrically carried by the shaft and located between the prongs of the body, a second shaft passing through holes in the prongs, a grooved member attached to said second shaft, the groove of which receives the eccentric pin, a cutting member on the outer end of the second shaft and a curved blade attached to one side of the body and having a hooked-shaped part forming a recess for receiving the cutting member whereby the material to be cut is forced against the cutting edge of the blade by the cutting member during the reciprocating movement of the parts.

In testimony whereof I affix my signature.

A. HEXDALL.
